UNITED STATES PATENT OFFICE.

WILLARD T. SEARS, OF MONTCLAIR, NEW JERSEY, ASSIGNOR TO NILES-BEMENT-POND COMPANY, OF NEW YORK, N. Y., A CORPORATION OF NEW JERSEY.

RADIAL DRILLING MACHINE.

Application filed May 15, 1920. Serial No. 381,556.

To all whom it may concern:

Be it known that I, WILLARD T. SEARS, a citizen of the United States, residing at Montclair, in the county of Essex and State 5 of New Jersey, have invented certain new and useful Improvements in Radial Drilling Machines, of which the following is a specification.

This invention relates to drilling machines 10 of the radial type wherein a drill-supporting arm is vertically adjustably supported on a column, such arm being adapted to be adjusted about the axis of the column as a center and to be secured rigidly to the 15 base of the machine during the drilling operation.

It is an object of the invention to provide 20 improved means for clamping the arm of a drilling machine in its adjusted position about the axis of the column during the drilling operation.

Another object of the invention is to provide 25 an arm and column clamping means which while in clamping position is held under a constant tension tending to tighten the clamp.

More specifically it is an object of the invention to provide an arm and column clamping means, an electric operating motor therefor and a motor controlling switch 30 which in its open position is adapted to leave a reduced amount of current on the motor tending to tighten the clamping means.

Another object of the invention resides in 35 providing a construction wherein sufficient energy is stored up during the initial clamping operation for holding the clamping means under a constant clamping tension during the drilling operation.

Further and more specific objects of the invention will become apparent as the description proceeds.

Referring to the drawings:

Figure 1 is an elevation of a drilling machine embodying the invention.

Fig. 2 is an enlarged fragmentary side elevation of the base of the machine.

Fig. 3 is a transverse horizontal section 50 thereof on the line 3—3 of Fig. 2.

Fig. 4 is a longitudinal vertical section taken on the line 4—4 of Fig. 3.

Fig. 5 is a diagram of the electrical con-

nctions for controlling the main and clamping motors.

Fig. 6 is a side elevation of the clamping motor switch shown in Fig. 5.

Fig. 7 is a fragmentary horizontal section of a modified form of the invention.

Fig. 8 is a cross section thereof on the line 8—8 of Fig. 7.

Fig. 9 is a fragmentary horizontal section of another modified form of the invention.

Fig. 10 is a cross section thereof on the line 10—10 of Fig. 9.

Drilling machines, when in operation, are subjected to considerable vibration which tends to loosen the clamping means holding the drill arm in the working position to which it has been previously adjusted. One 70 object of the present invention is to provide a structure wherein this objection is removed and the structures outlined in the drawings are illustrative of such mechanism. These structures are adapted not only to 75 clamp and hold the drill arm and column in the clamped working position but are also adapted to hold the clamping means in a manner constantly tending to tighten such means. By this construction any looseness 80 of the parts or of the clamping mechanism caused by the said vibration or otherwise is immediately taken up with the result that the drill arm and column are always held securely clamped during the entire operation of the machine.

Referring more specifically to the drawings and particularly to the construction illustrated in Fig. 1, 1 represents the base 90 of the drilling machine supported on a bed 2. Mounted upon the base for movement about a vertical axis is a column 3. Preferably this column is divided or formed in two parts as shown in my Patent 1,071,590, dated August 26th, 1913. Supported on the 95 column and vertically movable with respect thereto is a horizontal arm 4 along which is slidably a saddle 5 carrying a head provided with a rotatable drill spindle 6. Preferably the arm 4 or a carrying member 100 therefor extends through the column between the two parts thereof and directly supports a gear casing 7 and an electric motor 8. From the motor 8 power is transmitted through gearing in the casing 7 to 105 the main power shaft 9 extending longitudi-

dinally of the arm and thence to the spindle 6. The mechanisms thus far described do not of themselves constitute any part of the present invention and they can be considerably modified as required.

The column 3 preferably is provided with an extension 10 which projects downward into the base parts 2 and 1. This extension is engaged by two bearings which serve to hold the column in axially fixed position and which at the same time permit turning movement. At 11 there is a roller bearing interposed between the extension 10 and the upper part of the base section 2. At 12 there is a roller bearing interposed between the lower end of the extension 10 and a cupped plate 13 secured to the lower base section 1.

For carrying the weight of the column and associated parts during turning movement, I provide a series of centrally disposed devices. As illustrated, there is an anti-friction column support in the form of a ball thrust bearing 14 which rests upon the before mentioned plate 13. Engaging the top race of the ball bearing is a vertical tube 15, this tube extending through a central aperture in the projection 10 and being freely movable therein. Supported on the top of the tube 15 is a coil spring 16 and this coil spring in turn supports a second vertical tube 17. The tube 17 at its top engages a bushing 18 which has threaded engagement with the column.

The spring 16 is sufficiently powerful to carry the entire weight of the column and associated parts when the clamping mechanism is released. The bottom of the column 3 is provided with a horizontal surface 19 adapted under certain conditions to engage a horizontal surface 20 on the top of the base section 2. In assembling, the surfaces 19 and 20 will be initially in contact. The bushing 18 is then turned so as to transfer the weight of the column from the base 2 to the vertical tube 17 and thence to the spring 16 and the ball bearing 14. The column is thus supported with the surfaces 19 and 20 entirely out of engagement. This construction is similar in principle to that described in my Patent No. 1,376,169, dated April 26th, 1921, but is different in certain important respects. One feature of difference is that the several column-supporting devices are so constructed and arranged as to leave an unobstructed central vertical aperture through the base and the lower part of the column. Under some circumstances it is desirable to modify the drive mechanism by omitting the electric motor 8 and by substituting a vertical drive shaft. The construction described makes it possible for the vertical drive shaft to be put in place in the central vertical aperture referred to.

The positions and relative weights of the

motor and of the arm together with the saddle and drill head are such that under ordinary conditions the resultant center of gravity is approximately at the center of the column and therefore vertically above the ball bearing 14. With the surfaces 19 and 20 out of engagement and with the weight of the parts substantially balanced on the bearing 14, it is possible to swing the column and arm very easily. After the arm has been swung to the desired position the column is clamped by the mechanism to be now described. The clamping mechanism is vertically acting, viz, applies pressure to the column downward in opposition to the spring, thus forcing the surface 19 into a direct clamping engagement with the surface 20.

Carried by the extension 10 near the bottom thereof, is a ring 21 having a downward and outward inclined upper surface. Preferably the ring is provided with spaced notches 22, 22 and the extension 10 is provided with similarly spaced lugs 23, 23. In assembling the notches 22 of the ring are brought into alignment with the lugs 23, 23 of the projection, thus permitting the ring to be moved upward to the level shown. Then the ring is turned so that the parts thereof between the notches will rest upon the lugs. For holding the ring in this position there is provided a key 24 engaging a keyway in the extension 10.

The base section 2 is provided with an inwardly extending flange 25 having a horizontal bottom surface positioned immediately above the top surface of the ring 21. Interposed between the ring 21 and the flange 25 is a split ring 26 having bottom and top surfaces adapted respectively to engage the top surface of the ring 21 and the bottom surface of the flange 25. Preferably, as shown, the top surface of the ring 21 is cut away at opposite quadrants so that there will be contact between the ring 21 and the ring 26 only at the remaining quadrants 27 and 27^a. A lug 28 on the base section 2 projects into a notch in the ring 26 to prevent the ring from turning. The ring 26 carries two apertured ears 29 and 30 through which extends a threaded rod 31. A pin 32 and a screw 32^a projecting through a slot in the rod and into a sleeve thereon prevents the rod 31 from turning. At one end the rod 31 is engaged by a threaded handle 33 and at the other end it is engaged by a threaded sleeve 34, this sleeve being adapted to be operated by a clamping motor 35 as shown in the drawing. The split clamping ring can therefore be operated either by the handle 33 or by power means as the motor 35.

As shown in Figs. 1, 2 and 3, the clamping motor 35 is mounted on the machine base on which is also mounted a bearing 36 for the worm wheel 37. The worm wheel is

driven by a worm 37^a on the motor shaft, as illustrated. The hub 38 of the worm wheel is recessed to receive therein the threaded clamping sleeve 34 and its co-operating parts. This sleeve is splined for longitudinal movement within the hub 38 and between the end thereof and a bushing and nut 39 on the extension 40 of the rod 31 is interposed a compression spring 41. This spring serves as a cushion or shock absorber during the unclamping operation of the motor. The motor 35 is operated in a forward direction to turn the threaded sleeve 34 and clamp the column in working position. This clamping operation is allowed to continue until the motor becomes stalled, whereupon the motor controlling switch is preferably thrown to leave a reduced amount of current on the motor tending continually to tighten the clamping sleeve 34. The stalling or stopping of the motor may be accomplished merely by the tightening of the clamping screw in the clamping operation, by limiting the rotation of the screw in any desired manner or the motor may be stopped by any other desired means. It should, of course, be understood that the invention in its broad aspect also contemplates the use of the clamping mechanism without leaving any electric current on the motor after the clamp has been set to its clamping position. The mechanical connection, comprising the worm and worm wheel and clamping screw, makes such operation possible since such construction prevents the clamping mechanism from becoming loose or the motor from rotating backwardly when the electric current is turned off the motor.

In Figs. 5 and 6 I have diagrammatically illustrated the electrical connections for controlling the main motor 8 and the clamping motor 35. 42 and 43 respectively illustrate the main motor switch and the clamping motor switch. A and B represent the terminals from which source the electrical energy is received. The terminal B is connected directly to the main motor while the terminal A passes through the main switch 42 which controls the operation of the main motor through the rheostat 42^a thereof. C and D represent the circuit to the clamping motor. In order to avoid the possibility of accidentally leaving the circuit to the clamping motor closed when the operator is through with the machine, I preferably pass the connection C of the clamping motor through the main motor switch in such manner that electric current is delivered to the clamping motor only when the main motor switch is closed. As illustrated, this construction comprises a contact sector 44 adapted to be engaged by a contact piece 44^a on the lever of the main switch 42.

The clamping switch 43 comprises a base and four pairs of poles a, a', b, b', c, c', and d, d' mounted thereon and a double switch knife pivoted to the poles a and a' and comprising a pair of knives e and a pair of knives f, the latter also serving as a handle for the switch. The switch is normally held in an open position, as illustrated in Fig. 6, by means of the springs g, g'. The terminals C and D enter the clamping switch at the poles a, a' and the other poles are connected to the clamping motor terminals, as illustrated in the drawing, in the following manner: When the knives e are engaged with the poles b, b' the current passes directly to the clamping motor through the poles a, a', knives e, poles b, b' and wires E and F. When the knives f are engaged with the poles d, d' the current passes reversely to the motor through the poles a, a', knives f, poles b', b (through the crossed wires x, x') and wires E and F. When the switch is in the intermediate position, illustrated in Fig. 6, the current passes directly to the motor through the poles a, a', knives f, poles c, c', poles b, b' (through the resistance coil X and wire x') and wires E and F. To clamp the drill arm and column, the motor is operated directly through the poles b, b', and after the clamping operation is completed and the motor is stalled, the clamping switch is thrown to the open position illustrated in Fig. 6 wherein the current passes through the resistance coil X and continues directly to the motor but in reduced amount, which causes a clamping tension on the motor tending at all times to take up any looseness in the clamping parts and hold the arm and column securely clamped.

In Fig. 7, I have illustrated a modified form of my invention. In this construction, I provide a frictional drive for the threaded clamping sleeve 34. Such mechanism herein comprises a worm wheel 45 frictionally mounted between a shoulder 46^a on the rotary driving hub 46 and a slidable sleeve 47 thereon. By means of a spring 47^a and its adjusting collar 47^b the sleeve is held in the desired frictional contact with the worm wheel. This construction is otherwise like that illustrated in Fig. 3 wherein the threaded sleeve 34 is driven by lugs 34^a engaging longitudinal grooves in the hub 46. Instead of stalling the motor as in the above described construction the motor is allowed to run, preferably at a reduced speed, while the drill arm and column are clamped and drilling operations are being performed. The clamping tension of the spring 47^a may be regulated to the proper tension to firmly clamp the arm and column and the constant rotation of the worm wheel 45 tends at all times to take up any looseness in the clamping mechanism and hold the arm and column securely clamped.

In Fig. 8, I have illustrated another form

of the invention wherein means is provided for storing up sufficient energy during the initial clamping operation for holding the clamping means under a constant clamping tension during the drilling operation. This means preferably comprises a spring as illustrated. The worm wheel 48 herein is recessed very similarly to that shown in Fig. 3. An element 49 is splined within the 10 worm wheel hub and such element is itself recessed at 49^a to receive the threaded clamping sleeve 50 therein. The sleeve 50 has an annular flange 51 thereon, and a cap 52 about the sleeve 50 and abutting against the 15 outer face of this flange is secured to the outer end of the element 49 whereby the element 49 and sleeve 50 are held in a relatively fixed position longitudinally. Between the flange 51 and the bottom of the recess 49^a, the element 49 and sleeve 50 are provided with inwardly and outwardly extending lugs 53 and 54 respectively. A tension spring 55 surrounds the sleeve 50 and has its ends secured to the element 49 and the 20 sleeve 50 respectively.

In operation, rotation of the worm wheel 48 in the forward direction first operates to rotate the threaded clamping sleeve 50 through the spring 55. When the resistance offered by the clamping mechanism is sufficient, the element 49 rotates relatively to the sleeve 50 whereby the spring 55 is wound up and placed under tension tending to rotate the sleeve 50 in a forward and clamping direction. After nearly a complete relative rotation of the element 49, the lug 53 thereon comes into contact with the lug 54 on the sleeve 50 and positively completes the clamping operation which is preferably continued 30 until the motor becomes stalled. The current may and preferably is then turned entirely off the motor which through the worm and worm wheel 48 holds the elements in the clamping position. The spring 55 being under tension constantly tends to tighten the threaded clamping sleeve whereby any looseness is immediately taken up and the column is firmly held in clamping position.

What I claim is:

50 1. In a drilling machine, the combination of a base, a column supported thereon, an arm projecting horizontally from the column, drilling mechanism carried by the arm, clamping mechanism for securing the arm from rotation relative to the base, and continuous rotary power means including a rotary power shaft operatively connected to the clamping mechanism for operating and holding the same under a clamping tension tending to tighten the clamp when in its clamping position.

60 2. In a drilling machine, the combination of a base, a column supported thereon, an arm projecting horizontally from the column, drilling mechanism carried by the arm,

clamping mechanism comprising screw means for securing the arm from rotation relative to the base and continuous rotary power means including a rotary power shaft operatively connected to the screw means for operating and holding the same under a clamping tension tending to tighten the screw means and clamp when in the clamping position.

3. In a drilling machine, the combination 75 of a base, a column rotatably supported thereon, an arm projecting horizontally from the column, drilling mechanism carried by the arm, clamping mechanism for securing the column from rotation on the base, a rotary motor for operating the clamping mechanism, and means whereby the motor holds the clamping mechanism under a clamping tension tending to tighten the clamp when in its clamping position. 80

4. In a drilling machine, the combination 85 of a base, a column supported thereon, an arm projecting horizontally from the column, drilling mechanism carried by the arm, clamping mechanism comprising screw 90 means for securing the arm from rotation relative to the base, a rotary motor for operating the screw means, and means whereby the motor holds the clamping mechanism under a clamping tension tending to tighten 95 the screw means and clamp when in the clamping position.

5. In a drilling machine, the combination 100 of a base, a column supported thereon, an arm projecting horizontally from the column, drilling mechanism carried by the arm, clamping mechanism comprising screw means for securing the arm from rotation relative to the base, a rotary motor, a mechanical connection between the motor and 105 screw means comprising a worm on the motor shaft engaging a worm wheel operatively connected to the screw means, and means whereby the motor holds the clamping mechanism under a clamping tension tending to 110 tighten the clamp when in the clamping position.

6. In a drilling machine, the combination 115 of a base, a column rotatably supported thereon, an arm projecting horizontally from the column, drilling mechanism carried by the arm, a clamping ring surrounding the column and adapted to secure the column from rotation on the base, operating means engaging the ends of the ring, a rotary motor for operating the said means, and means whereby the motor holds the operating means under a clamping tension tending to tighten the operating means and ring when in the clamping position. 120

7. In a drilling machine, the combination 125 of a base, a column rotatably supported thereon, an arm projecting horizontally from the column, drilling mechanism carried by the arm, a clamping ring surround-

- ing the column and adapted to secure the column from rotation on the base, screw means engaging ends of the ring, a rotary motor for operating the screw means, and 5 means whereby the motor holds the screw means under a clamping tension tending to tighten the screw means and ring when in the clamping position.
8. In a drilling machine, the combination 10 of a base, a column rotatably supported thereon, an arm projecting horizontally from the column, drilling mechanism carried by the arm, and means including a rotary electric motor for clamping the column 15 against rotation on the base, the motor being automatically stopped when the clamping means has been drawn tightly into its clamping position.
9. In a drilling machine, the combination 20 of a base, a column rotatably supported thereon, an arm projecting horizontally from the column, drilling mechanism carried by the arm, clamping mechanism for securing the column from rotation on the base, a 25 rotary motor for operating the clamping mechanism, and a mechanical connection between the motor and the clamping mechanism whereby the clamping mechanism when drawn tightly into its clamping position stalls the motor.
10. In a drilling machine, the combination 30 of a base, a column rotatably supported thereon, an arm projecting horizontally from the column, drilling mechanism carried by the arm, clamping mechanism for securing the column against rotation on the base, a rotary motor, and a mechanical connection 35 between the motor and clamping mechanism, the mechanical connection being of such construction that the clamping mechanism cannot become loose or rotate the motor backward when the electric current is turned off the motor.
11. In a drilling machine, the combination 40 of a base, a column rotatably supported thereon, an arm projecting horizontally from the column, drilling mechanism carried by the arm, clamping mechanism for securing the column against rotation on the base, a rotary motor, and a mechanical connection 45 comprising a worm and worm wheel between the motor and the clamping mechanism.
12. In a drilling machine, the combination 50 of a base, a column rotatably supported thereon, an arm projecting horizontally from the column, drilling mechanism carried by the arm, clamping mechanism for securing the column from rotation on the base, a rotary motor for operating the clamping 55 mechanism, and a resilient mechanical connection between the motor and the clamping mechanism.
13. In a drilling machine, the combination 60 of a base, a column rotatably supported thereon, an arm projecting horizontally from the column, drilling mechanism carried by the arm, clamping mechanism comprising screw means for securing the column non-rotatably to the base, rotary power means for operating the screw means, and 65 means whereby the screw means in clamping position is held under clamping tension less than the normal operative strength of the power means.
14. In a drilling machine, the combination 70 of a base, a column supported thereon, an arm projecting horizontally from the column, drilling mechanism carried by the arm, clamping mechanism for securing the arm from rotation relative to the base, a rotary motor for operating the clamping mechanism and a motor controlling switch adapted in its open position to leave a reduced amount of current on the motor 75 whereby the clamping means is held under a clamping tension tending to tighten the same when the arm is secured to the base.
15. In a drilling machine, the combination 80 of a base, a column rotatably supported thereon, an arm projecting horizontally from the column, drilling mechanism carried by the arm, clamping mechanism comprising screw means for securing the column non-rotatably to the base, a rotary motor for operating the screw means, and a motor controlling switch adapted in its open position to leave a reduced amount of current on the motor 85 whereby the clamping means is held under a clamping tension tending to tighten the same when the arm is secured to the base.
16. In a drilling machine, the combination 90 of a base, a column rotatably supported thereon, an arm projecting horizontally from the column, drilling mechanism carried by the arm, clamping mechanism comprising screw means for securing the column non-rotatably to the base, a rotary motor for operating the screw means, and a motor controlling switch adapted in its open position to leave a reduced amount of current on the motor 95 whereby the clamping means is held under a clamping tension tending to tighten the screw means and clamp when the column is non-rotatably secured to the base.
17. In a drilling machine, the combination 100 of a base, a column supported thereon, an arm projecting horizontally from the column, drilling mechanism carried by the arm, clamping mechanism for securing the column from rotation on the base, a rotary motor for operating the clamping mechanism, and a spring interposed between the motor and the clamping mechanism whereby during the initial clamping operation sufficient energy is stored in the spring to 105 hold the clamp tightly engaged during the drilling operation.
18. In a drilling machine, the combination 110 of a base, a column supported thereon, an arm projecting horizontally from the column, drilling mechanism carried by the arm, clamping mechanism comprising screw means for securing the arm from rotation relative to the base, a rotary motor for operating the screw means, and a spring interposed between the motor and screw means whereby during the initial clamping operation sufficient energy is stored in the spring to 115 hold the screw means tightly engaged and under a clamping tension during the drilling operation.
19. In a drilling machine, the combination 120 of a base, a column supported thereon, an arm projecting horizontally from the column, drilling mechanism carried by the arm, clamping mechanism comprising screw means for securing the column non-rotatably to the base, rotary power means for operating the screw means, and means whereby the screw means in clamping position is held under clamping tension less than the normal operative strength of the power means.
20. In a drilling machine, the combination 125 of a base, a column supported thereon, an arm projecting horizontally from the column, drilling mechanism carried by the arm, clamping mechanism comprising screw means for securing the column non-rotatably to the base, rotary power means for operating the screw means, and means whereby the screw means in clamping position is held under clamping tension less than the normal operative strength of the power means.

tion of a base, a column supported thereon, an arm projecting horizontally from the column, drilling mechanism carried by the arm, clamping mechanism comprising screw means for securing the arm from rotation relative to the base, a rotary motor for operating the screw means, a mechanical connection between the motor and the screw means comprising a worm on the motor shaft engaging a worm wheel operatively connected to the screw means, and a spring interposed between and having its ends respectively connected to the worm wheel and the screw means, whereby during the initial clamping operation sufficient energy is stored in the spring to hold the screw means tightly engaged and under a clamping tension during the drilling operation.

19. In a drilling machine, the combination of a base, a column supported thereon, an arm projecting horizontally from the column, drilling mechanism carried by the arm, clamping mechanism comprising screw means for securing the arm from rotation relative to the base, a rotary motor for operating the screw means, a mechanical connection between the motor and the screw means comprising a worm on the motor shaft engaging a worm wheel operatively connected to the screw means, the connection between the worm wheel and the screw means comprising a lug on the screw means adapted to be engaged and driven by a lug operated from the worm wheel, and a spring interposed between and having its ends respectively connected to the worm wheel and the screw means, whereby during the initial clamping operation, sufficient energy is stored in the spring to hold the screw means tightly engaged and under a clamping tension during the drilling operation.

20. In a drilling machine, the combination of a base, a column supported thereon, an arm projecting horizontally from the column, drilling mechanism carried by the arm, clamping mechanism comprising screw means for securing the arm from rotation relative to the base, a rotary motor for operating the screw means, a mechanical connection between the motor and the screw means comprising a worm on the motor shaft engaging a worm wheel operatively connected to the screw means, a member mounted on the screw means and splined to the worm wheel, such member and screw means having inwardly and outwardly extending lugs respectively adapted to engage and drive the screw means, and a spring coiled around the screw means and having its ends respectively connected to the worm wheel and the screw means whereby during the initial clamping operation, before the said lugs engage to drive the screw means positively, sufficient energy is stored in the spring to hold the screw means tightly en-

gaged and under a clamping tension during the drilling operation.

21. In a drilling machine, the combination of a base, a column supported thereon, an arm projecting horizontally from the column, drilling mechanism carried by the arm, clamping mechanism for securing the arm from rotation relative to the base, a main motor for operating the drilling mechanism, a clamping motor for operating the clamping mechanism, a switch for controlling the main motor, a switch for controlling the clamping motor, and connections between the switches whereby when the main switch is open the circuit to the clamping switch is also open.

22. In a drilling machine, the combination of a base, a column rotatably supported thereon, an arm projecting horizontally from the column, drilling mechanism carried by the arm, clamping means surrounding the column and having the ends thereof engaged by screw means, a rotary motor for operating the screw means, and a handle also operatively connected to the screw means, such means being adapted to be operated by either the motor or the handle to secure the column and base from relative rotary movement.

23. In a drilling machine, the combination of a base, a column rotatably supported thereon, an arm projecting horizontally from the column, drilling mechanism carried by the arm, clamping means surrounding the column and having the ends thereof engaged by screw means comprising a non-rotary screw with a clamping nut at each end thereof, a motor operatively connected to one clamping nut, and a handle operatively connected to the other clamping nut, the clamping means being adapted to be operated by either the motor or handle to secure the column and base from relative rotary movement.

24. In a drilling machine, the combination of a base, a column rotatably supported thereon, an arm projecting horizontally from the column, drilling mechanism carried by the arm, clamping means surrounding the column and having the ends thereof engaged by a non-rotary screw, a power driven nut threaded on the screw, and a compression spring between the outer end of the nut and the outer end of the screw adapted to cushion the momentum of the operating parts in the unclamping operation.

25. In a drilling machine, the combination of a base, a column rotatably supported thereon, an arm projecting horizontally from the column, drilling mechanism carried by the arm, means normally raising the column from direct engagement with the base, a rotary motor, a clamping mechanism comprising screw means adapted to be operated by the motor for drawing the column

into direct engagement with the base and for securing the column from rotation on the base, and means whereby the motor during the initial clamping operation stores up sufficient energy to hold the screw means under a clamping tension tending to tighten the screw means and clamp when in the clamping position.

26. In a drilling machine, the combination of a base, a column rotatably supported thereon, an arm projecting horizontally from the column, drilling mechanism carried by the arm, resilient means normally raising the column from direct engagement with the base, clamping mechanism comprising a clamping ring surrounding the column and having the ends thereof connected by screw means for securing the column non-rotatably to the base, a rotary motor for operating the screw means to draw the column into engagement with the base against the action of the resilient means and to secure the column from rotation on the base, and means whereby the motor during the initial clamping operation stores up sufficient energy to hold the screw means under a clamping tension tending to tighten

the screw means and ring when in the clamping position.

27. In a drilling machine, the combination of a base, a column rotatably supported thereon, an arm projecting horizontally from the column, drilling mechanism carried by the arm, a compression spring interposed between the column and base and adapted to normally raise the column from direct supporting engagement with the base, clamping mechanism comprising a clamping ring surrounding the column and having the ends thereof connected by screw means for securing the column non-rotatably to the base, a rotary motor for operating the screw means to draw the column into engagement with the base against the action of the spring and to secure the column from rotation on the base, and means whereby sufficient energy is stored up during the clamping operation to hold the screw means in clamping position under a clamping tension less than the normal operating strength of the motor.

In testimony whereof, I hereto affix my signature.

WILLARD T. SEARS.
